poration of Connecticut

Filed Feb. 17, 1964, Ser. No. 345,370

2 Claims. (Cl. 206—56)

The present invention relates to a dispensing device and more particularly to an elongate device for dispensing slender sticks of cosmetic or the like material.

Heretofore, dispensing devices have been provided for articles of the type herein involved but they have been difficult and expensive to manufacture and assemble.

The present invention has for an object the provision of a dispenser for slender articles which is simple in operation and construction, can be readily manufactured, and can be quickly and easily assembled, all of which tends to reduce the cost of the device. This is a tremendous advantage in such a highly competitive art.

In carrying out the invention, the dispensing device is formed of a minimum number of parts, each of which is extremely simple and can be readily assembled without special tools or fixtures. Further, the construction of the parts is such that they lend themselves to being readily molded from thermoplastic materials if desired.

Other features and advantages of the invention will be apparent from the specification and claims when considered in connection with the accompanying drawings in which:

FIGURE 1 is a longitudinal sectional view of the dispensing device of the present invention with the cover in position thereon.

FIG. 2 is a view, partly in section, showing the cover removed and the article partially dispensed from the end thereof.

FIG. 3 is a sectional view taken along lines 3—3 of FIG. 1.

FIG. 4 is a sectional view taken along lines 4—4 of FIG. 1.

FIG. 5 is a sectional view taken along lines 5—5 of FIG. 1.

FIG. 6 is a view, partly in section, showing another form of the dispenser of the present device.

FIG. 7 is a sectional view of the cap portion taken along lines 7—7 of FIG. 6.

FIG. 8 is a sectional view taken along lines 8—8 of FIG. 6.

As shown in the drawings, the present invention is directed to a slender elongate dispensing device 10 for dispensing slim articles or sticks 11 of cosmetic or medicinal compositions usually having a greasy or waxy texture. For example, the cosmetic articles can be lipsticks, eyebrow pencils, eye shadow and eyeliner materials, pomades and the like. The medicinal materials can be sticks for providing relief for chapped lips and other similar uses.

The sticks 11 are mounted in a cup-shaped carrier 12 having a screw 13 rigidly connected thereto and projecting therefrom. While the carrier and screw can be made of metal, they are preferably molded from a thermoplastic material such as acetal resin with the carrier and screw formed integrally. The carrier is slidably mounted in a body 14 which is open at one end and forms a tubular article-receiving portion 15. The other end is closed by a transverse wall 16 having a central aperture 17 therein through which the screw projects when the carrier is assembled thereon. While the central aperture may be provided with at least one flat wall, in the preferred form of the invention it is provided with opposed flat walls 18, as shown in FIG. 4. The screw is provided with corresponding flat surfaces 19 so that, while the screw can

2

slide longitudinally in the body, it is held against rotation with respect to the body, thus maintaining the carrier and the article mounted therein against rotation and properly oriented on the body as will be explained.

5 A feed nut 20 is threaded on the projecting screw 13 and, in normal position, is located adjacent the transverse wall 16. Although the nut can be made of metal, it is at present preferred to mold it from a thermoplastic material, such as nylon.

10 In the preferred form of the invention the body is provided with a finger grip portion in the form of a pair of annular ribs 21 spaced along the body from the end having the transverse wall 16 which provides a means for holding the dispensing device while it is manipulated to project or retract the article. In the preferred form of the invention the outer surface 22 of the body between the ribs 21 and the end having the transverse wall is cylindrical and is adapted to telescopically receive a tubular end portion 23 of an elongate operating member 24 for rotation thereon.

15 The elongate operator is provided with a central bore 25 to receive the screw 13 and has in the interior thereof an enlargement of the bore forming an open-ended socket 26 for receiving the feed nut and holding it adjacent the transverse end wall when the operator is in position on the body, all as shown in FIGS. 1 and 2. While the socket can be provided with any driving means for engaging and rotating the feed nut, it is at present preferred to provide the feed nut and socket with cooperating flat surfaces 27, 28, as shown in FIG. 5, to effect the driving of the same.

20 In order to hold the operator in position on the body and prevent it from moving longitudinally with respect to the body when in assembled position, means are provided for releasably holding the two together. In the illustrated form of the invention the telescoped engaging surfaces of the body and operator are provided with an annular groove 29 and cooperating rib 30 which will snap together incident to the assembly thereof and effectively prevent separation of the operator from the body while 25 permitting relative rotation therebetween.

25 As shown in FIGS. 1 and 2, it is preferred to slant the open end of the tubular portion 15 of the body at a predetermined angle as at 31 and the end 32 of the article at a corresponding slant so that in normal position they lie in a plane inclined to the longitudinal axis of the body. Since the article is held against rotation in the body by the screw cooperating with the flat walls of the aperture, it will maintain its relative position in all projected positions as shown in FIG. 2.

30 If desired, a usual tubular protective cover 33, as shown in FIG. 1, can be telescoped over the tubular end portion 15 of the body to provide a closure for protecting the article.

35 From the foregoing it will be apparent that the device 60 of the present invention comprises a minimum number of operative elements which are simple in design and can be readily manufactured and assembled to produce an effective dispensing device. The simplicity and character of the cooperating elements is such that they can be readily handled and molded from thermoplastic materials, such as polystyrene, polypropylene, nylon and acetal resins, in plural cavity multi-part molds so that they can be produced at a minimum of expense and can be assembled with great facility.

40 In assembling the elements, the carrier and screw are inserted into the tubular body with the screw passing through the aperture 17 in the wall 16. The feed nut is

threaded on the screw to a point adjacent the transverse wall. This effectively holds these elements in assembled relation to facilitate the handling thereof and permits the remaining assembly operation to be greatly expedited. The operator 24 is then slipped over the end of the body and the screw will pass into the bore 25 and the nut 20 will readily move into the open-ended socket 26 as the telescoped portions of the body and operator are assembled and snapped into interlocked relation.

While the carrier cup can be used as a part of the mold for the article as it is formed, it is at present preferred to mold the articles separately and to mount them into the carrier cup after the operator and body have been assembled and the carrier moved to its outermost position on the body. The mounting is greatly facilitated by the fact that the carrier is held against relative rotation with respect to the body by the flat faces on the screw cooperating with the flat sides of the apertures 17 so that the article can be properly positioned and oriented, particularly where slanted end body and articles are used, and maintained in said relation at all times. Thereafter, the article is retracted into the body and the cap 33 is inserted over the tubular body to enclose the article.

A further advantage of molding the operator and cover from plastic material resides in the fact that the exterior design or ornamentation of the dispenser can be provided during the molding thereof so that an individual style and distinctive appearance of each of the dispensing devices can be readily attained. If desired, additional ornamentation, such as metal bands or the like, can be applied to the surface of said molded parts.

In the form of the invention shown in FIGS. 6-8, means is provided for preventing inadvertent operation of the device as may damage the article. In this form of the invention many of the parts, such as the carrier 12, screw 13 and nut 20 are the same as in FIG. 1 and are designated by the same numeral. The body 14 is substantially the same as in FIG. 1 except that the projecting annular ribs 21 forming the finger grip portions have been removed and the outer surface is cylindrical from end to end. If desired, the cylindrical body can be knurled or roughed at 21a to form a finger grip therefor. The operator 24 is of the same construction as in FIG. 1 with the exception that at its open outer end it is reduced to form a neck 35 projecting at the end of the body. The cover is the same except that it has its lower open end extended so as to have a portion 36 adapted to telescope over the neck 35 at the end of the operator.

As shown in FIG. 8, the telescoped portions of the neck and cover body are provided with interlocking means for preventing relative rotation between the cover and operator. In the herein illustrated form of the invention this means comprises interior cavities 37 in the wall of the cover which open at the end of the cover to receive projections 38 on the neck. The projections are of such a size that they freely fit into the cavities within the cover to interlock therewith without applying any outward pressure to the cover as might produce cracking of the cover when made of plastic material.

Since there is no pressure at the overlapped portions which might frictionally hold the cover in place, it is herein preferred to form internal friction pads 39, as shown in FIG. 7, which are located adjacent the closed end of the cover and in position to engage the tubular end of the body as shown in FIG. 6. This will frictionally hold the cover and the tube together to prevent inadvertent relative longitudinal movement. With the tubular body, cover and operator so held together, inadvertent relative rotation of the operator on the body as might feed the article against the cover and damage it will be prevented.

Variations and modifications may be made within the scope of the claims and portions of the improvements may be used without others.

I claim:

1. A dispensing device for an elongate stick-like article comprising a hollow body of plastic material forming an article-receiving tube open at one end and having a transverse wall at the other end having a central aperture therein provided with at least one flat side wall, said body adjacent said other end being cylindrical, an operator of plastic material having a tubular end and a bore of reduced diameter extending inwardly therefrom, said tubular end telescopically receiving said cylindrical portion of the body to be mounted thereon for relative rotation, cooperating projection and recess means on said telescoped portions of the body and operator to releasably hold the body and operator against longitudinal separation, said resilient plastic material of the cooperating body and operator permitting the projection to snap into said recess incident to the telescoping thereof, said body having a finger grip configuration on the outer surface thereof adjacent the end of the operator mounted thereon, an article carrier having an article mounted thereon slidably mounted in the tube and having a screw rigidly connected thereto, said screw projecting through the central aperture in the body and into the bore in said operator and having at least one flat side to cooperate with the flat side wall of the aperture in the transverse wall to prevent rotation of the screw and carrier in the body, and a separate feed nut threaded on the projecting portion of the screw and normally located adjacent the transverse wall, said bore in said operator adjacent said tubular portion being enlarged and forming an open-ended socket receiving said nut having an end portion for engaging the nut when the operator is assembled on the body, said wall and end of the socket holding the nut in said normal position in said socket, said socket and nut having cooperating engaging side walls provided with means for preventing relative rotation between the operator and nut whereby rotation of said operator on said body, while the body is held by the finger grip configuration, causes the nut to cooperate with the screw and advance or retract the article carrier and cause the article mounted therein to be projected from or retracted within said body for use or storage.

2. A dispensing device for an elongate stick-like article comprising a hollow body forming an article-receiving tube open at one end and having a transverse wall at the other end having a central aperture therein provided with at least one flat side wall, said body having finger grip means spaced from said transverse wall with the outer surface of the body between said finger grip means and said wall being cylindrical, an operator having a tubular end and a bore of reduced diameter extending inwardly therefrom, said tubular end telescopically receiving said cylindrical portion of the body to be mounted thereon for relative rotation, cooperating means on said telescoped portions of the body and operator to releasably hold the body and operator against longitudinal separation, an article carrier having an article mounted thereon slidably mounted in the tube and having a screw rigidly connected thereto, said screw projecting through the central aperture in the body and into the bore in said operator and having at least one flat side to cooperate with the flat side wall of the aperture in the transverse wall to prevent rotation of the screw and carrier in the body, and a separate feed nut threaded on the projecting portion of the screw and normally located adjacent the transverse wall, said bore in said operator adjacent said tubular portion being enlarged and forming an open-ended socket receiving said nut and having an end portion for engaging the nut when the operator is assembled on the body, said wall and end of the socket holding the nut in said normal position in said socket, said socket and nut having cooperating engaging side walls provided with means for preventing relative rotation between the operator and nut whereby rotation of said operator on said body causes the nut to cooperate with the screw and

advance or retract the article carrier and cause the article mounted therein to be projected from or retracted within said body for use or storage, the end of the operator telescoped with said body having a smooth outer surface forming a neck thereon, and a tubular cover of molded plastic material having a closed end and an open end inserted over said article-receiving tube with the open end in telescopic relation with said neck, said cover having friction means on the interior thereof adjacent the closed end to engage said tube and hold the cover thereon against inadvertent longitudinal movement thereon and the engaging surfaces only of said telescoping neck and cover having cooperating internal cavities and projections for preventing relative rotation of said cover and operator with said cavities and projections nesting freely and without any outward pressure on the cover adjacent said open end.
